J. B. LAUGHLIN

HEAT RETAINING AND DISTRIBUTING ELEMENT

Filed Jan. 13, 1927

By Clarence A. O'Brien, Attorney

UNITED STATES PATENT OFFICE.

JAMES B. LAUGHLIN, OF BRADFORD, PENNSYLVANIA.

HEAT RETAINING AND DISTRIBUTING ELEMENT.

Application filed January 13, 1927. Serial No. 160,922.

This invention relates to an improved appliance or element designed for the purposes of heat retention and distribution of heated gases in furnaces, boilers, or other heating fixtures in which an open oil or gas flame is employed.

Briefly, the invention has particular reference to a body of appropriate shape and material which is to be placed over the burner in a combustion chamber and which serves as a device for the absorption, retention, and dissemination of heat, from the ignited gases.

The present invention is not to be confused with inventions similar in appearance, which constitute a part of a burner structure, and which are employed as mixers and fuel distributors to aid in combustion. Instead, it is a separate and independent body supported above the burner by appropriate means, for retention, distribution and dissemination of heat from the ignited gases when produced by a flame from any suitable source of fuel.

The chief feature of my invention is the provision of a refractory block containing layers or rows of bores, each layer of bores being at right angles to the layer above and the layer below. Because of this heat passes up through intersecting holes to the different layers of bores and also through the bores in different directions to sides of the fire chamber and produces an even heat distribution. The heat retaining and distributing element being characterized by the various layers of bores heats quickly and holds the heat.

The preferred embodiment of the invention as well as the structural features embodied therein, will become apparent from the following detailed description and drawings.

In the drawings:—

Figure 1 is a side view of a device constructed in accordance with the present invention, showing the manner in which it is adapted to be supported above a burner.

Fig. 2 is a central cross section taken approximately upon the plane of the line 2—2 of Fig. 1, looking in the direction of the arrows.

Fig. 3 is a top plan view of the block with a portion broken away and in section.

Referring now to the drawings in detail, it will be seen that the reference character

1 designates generally a burner of any suitable construction above which the invention generally designated by the reference character 2 is supported in any appropriate manner. The invention comprises a substantially circular body of fire clay of relatively large proportion with respect to the fires of the burner. This body is of a diameter, however, to permit its peripheral portion to be disposed in spaced relation to the surrounding wall of the fire box in which it is adapted to be suspended.

The body is formed in its flat top and bottom faces with substantially semi-circular grooves. The respective sets of grooves are disposed in parallelism with each other and extend in the same direction, for instance, from left to right in Fig. 1. The grooves in the top of the block are designated by the reference characters 3; while the grooves in the bottom are designated by the reference characters 4.

Two different groups of bores are formed in the block or body. For instance, one group comprises three layers of bores. These are shown for instance in Fig. 1. The bores of the top row are designated at 5, those of the central row at 6, and those in the bottom row at 7. It will be noticed that the bores in each layer are in the same horizontal plane but are so arranged as to dispose them in staggered relation with respect to the bores of the other layer. The sectional view in Fig. 2, which is taken to show these bores at right angles, to the disposition in Fig. 1, also brings out the fact that the top layer of bores intersects the bottom portions of the grooves 3, in such a manner as to provide openings affording communication between these top grooves 3 and the top bores 5 as shown better in Fig. 3.

The bores 7 of the lowermost row, which are also the largest in diameter, intersect the bottom grooves 4. Thus far, we have a circular body having parallel grooves in its flat top and bottom together with right angularly disposed bores intersecting these grooves.

The second group of bores is composed of two horizontal rows, the bores of the top row of this set being designated by the reference characters 8 and those of the bottom row being designated by the reference characters 9. The bores 9 are located between the aforesaid bores 7 and 6. These bores 9

extend at right angles to the bores 6 and 7, and intersect and communicate with the last named bores. The bores 8 extend at right angles to and intersect and communicate with the bores 5 and 6. From the foregoing description, it will be seen that I have evolved and produced an exceptionally simple and inexpensive heat retainer and distributor in the form of a circular block of fire clay, having flat top and bottom surfaces provided with spaced parallel grooves. The portion of the body between these grooves is formed with two groups of horizontal rows of bores, there being three rows in one group and two rows in the other group, making a total of five. The bores of the first group extend at right angles to the grooves and also at right angles to the bores of the second group.

It is believed that the construction, as well as the features and advantages and operation of the invention will be clear when considering the description in connection with the drawings. Therefore, a more lengthy description is thought unnecessary.

While the preferred embodiment of the invention has been shown and described, it is to be understood, that changes in the shape, size and proportions may be resorted

to without departing from the spirit of the 30 adjoined claim.

Having thus described my invention, what I claim as new is:—

A heat retention and distribution element in the form of a body of fire clay, having flat top and bottom surfaces provided with spaced parallel grooves, that portion of the body between the respective sets of grooves being provided with two layers of bores, one group comprising vertically 35 spaced horizontal rows of bores open through opposite sides of the body and disposed at right angles to said grooves, the bores of the two outer rows intersecting and communicating with the adjacent grooves, 40 and the second group of bores comprising two vertically spaced horizontal layers of bores extending in the same direction as said grooves, and at right angles to the bores of said first group, the bores of said second 45 group intersecting and being in communication with the top and bottom rows of bores in said first group and also intersecting and being in communication with the intermediate row of bores in the first group.

In testimony whereof I affix my signature.

JAMES B. LAUGHLIN.
